UNITED STATES PATENT OFFICE.

MAURICE BERNAYS JOHNSON, OF SAN ANTONIO, TEXAS.

WIRELESS-TELEPHONE SYSTEM.

996,090.

Specification of Letters Patent. Patented June 27, 1911.

Application filed October 6, 1910. Serial No. 585,544.

To all whom it may concern:

Be it known that I, MAURICE BERNAYS JOHNSON, a citizen of the United States, and a resident of San Antonio, in the county of Bexar and State of Texas, have made and invented certain new and useful Improvements in Wireless-Telephone Systems, of which the following is a specification.

My invention relates to wireless telephone systems, of the type wherein current travels through the ground, and the object thereof is to provide an improved wireless telephone system having signaling and talking circuits so arranged that it will be unnecessary 15 to operate a switch to connect in the receiver and transmitter alternately as a person listens or talks as has frequently been the case, the talking circuit, when established, being in condition for both receiving 20 and transmitting messages without change.

My invention is illustrated in the accompanying drawings and described in the following specification, and the distinguishing features thereof are particularly claimed in 25 the clauses of the claim.

In the drawing, the figure illustrates in diagram the preferred embodiment of my invention.

A and B are two wireless telephone stations, separated a considerable distance 30 from one another communication between the two being established through the ground.

Referring to the station A, 1 is an electric bell, 2, a two pole switch, 3, a single pole switch, 4 a battery of any form, which battery may be replaced by any other suitable source of electricity, and 5 is a telephone instrument of any suitable form, the instrument 35 shown being of the type which has the receiver and transmitter in series, with a hook switch for cutting out the receiver and transmitter and making a signaling circuit when the receiver is hung up.

The instruments thus far described are connected with the ground by two ground wires 6, 7, these being connected to the ground at some considerable distance apart, as is usual in such systems. Terminals such 50 as binding posts 8, 9, 10 are employed for convenience in connecting the telephone instrument 5 in circuit with the remaining portion of the apparatus, these, however, being provided so that a telephone instrument of common form may be used, the posts 8,

9 being bridged by a link 14, to cut out the signaling circuit of the instrument.

11 is a wire connecting the switch 2 with the terminal 9, 12 is a wire connecting the switch 2 and the binding post 10, and 13 is a 60 wire connecting the binding post 10 with the battery 4.

The instruments and circuits in the remote station B are similar to the instruments and circuits thus far described for the 65 station A, and without specifically referring to each element of the station B, prime numbers such as 1¹, 2¹, 3¹, etc., are used at B to designate instruments and circuits similar to those above described as in the 70 station A.

The switch arms of the switches 2, 2¹, are normally in their upper positions, and the switches 3, 3¹, are normally open. Such being the case, an operator at A signals the 75 station B by moving the switch arm of the switch 2 into its lower position and closing the switch 3, whereupon current will flow from battery 4 through switch 3 and wire 7 to ground; to the distant station B, 80 through ground wire 6¹, link 14¹, and wire 11¹, through switch 2¹, bell 1¹ and ground connection 7¹ to ground; back through the earth to the station A, through the ground connection 6, link 14 and wire 11 through 85 switch 2, wires 12, and 13 to the battery 4, thus completing the circuit and ringing bell 1¹, in the station B. During the signaling

step above outlined and also when a signal is sent from the station B to the station A 90 in a manner obvious from the above description, the telephone instruments 5, 5¹, are cut out by means of the switch controlled by the hook upon which the receiver normally hangs, so that current may not 95 flow through the telephone instruments while the instruments are used for signaling purposes. Upon receiving the signal as above, the operator at the station B will close the switch 3¹ and place the arm of the 100 switch 2¹ in its middle position, thus cutting out the bell 1¹, and take down the receiver of the telephone, and, the operator in the station A having done likewise, a talking circuit is established as follows: from 105 battery 4 through switch 3 and wire 7 to ground; through the ground to the distant station B; through ground wire 6¹, telephone instruments 5¹, wire 13¹, battery 4¹, switch 3¹, and ground wire 7¹, to ground; 110

through the ground to the station A; through ground wire 6, telephone instruments 5 and wire 13 to battery 4 thus completing the circuit, the telephone instruments being cut in, as will be understood, as the receivers are taken from their hooks.

Having thus described my invention and explained thereof the operation, I claim and desire to secure by Letters Patent—

- 10 In a wireless telephone system, a bell; a battery; two ground connections; a two pole switch 2 adapted to connect either said bell, or said battery, in circuit with said ground connections, or to break both said circuits;

a switch 3 for controlling said last named circuit; and a telephone instrument, the same being connected with said system but the circuit through which is normally broken.

Signed at New York, borough of Manhattan, in the county of New York and State of New York, this 30th day of September, A. D. 1910.

MAURICE BERNAYS JOHNSON.
